CLAIM

The ornamental design for a caliper for disc brakes, as shown and described.

DESCRIPTION

FIG. 1 is a perspective view of a caliper for disc brakes, showing our new design from the left side, front and bottom;

FIG. 2 is a bottom plan view thereof;

FIG. 3 is a top plan view thereof;

FIG. 4 is a front elevational view thereof;

FIG. 5 is a rear elevational view thereof;

FIG. 6 is a left side elevational view thereof; and,

FIG. 7 is a right side elevational view thereof.
